UNITED STATES PATENT OFFICE.

DANIEL D. WELLS, OF JACKSONVILLE, FLORIDA.

PEDEMOBILE.

No. 833,100.

Specification of Letters Patent.

Patented Oct. 9, 1906.

Application filed February 23, 1906. Serial No. 302,571.

To all whom it may concern:

Be it known that I, DANIEL D. WELLS, a citizen of the United States, residing at Jacksonville, in the county of Duval and State of Florida, have invented certain new and useful Improvements in Pedemobiles, of which the following is a specification.

My invention relates to means whereby individual locomotion, either for pleasure or business, may be effected upon smooth or comparatively rough surfaces, said means consisting of a wheel appliance to be attached to either or both feet of the person, as may be required.

15 The invention aims to devise a structure in which two wheels having a tandem arrangement of comparatively large diameter may be employed so as to facilitate travel over rough roads and pavements, as well as over smooth surfaces, an important factor being strength and durability, as well as to relieve the ankle of the strain incident to the use of said appliances.

25 The invention also aims to provide for proper steering, the structure being such as to enable the direction being controlled by shifting of the weight laterally to one side or the other of a medial line, the degree of deflection being proportionate to and governed 30 by the excess of weight upon one side or the other of said medial line.

35 The invention further provides for controlling of the speed either voluntarily or involuntarily, according as the user has perfect control or has lost control through any cause which would tend to throw the feet forward of the center of gravity and result in a fall if means were not provided for automatic control of the speed, which is accomplished by 40 means of a brake mechanism disposed so as to coöperate with one of the supporting-wheels, said brake mechanism being automatically set by the shifting of the weight from one end of the device to the other, preferably toward the heel.

45 The invention also provides means for maintaining the parts in normal position and for returning said parts to a given position after being moved therefrom by disturbing 50 forces either as a result of voluntary or involuntary action on the part of the user, said means being adjustable, whereby provision is had to adapt the same to the strength and weight of the user.

55 The invention consists of the novel structural features, details, and the conditions of

parts, which hereinafter will be more particularly set forth, illustrated, and finally embodied in the subjoined claims.

Referring to the accompanying drawings, 60 forming a part of the specification, Figure 1 is a side view of a pedemobile embodying the invention, a portion of the side brace or stay being broken away and showing the device fitted to the foot or limb. Fig. 2 is a front 65 view thereof. Fig. 3 is a top plan view of the device, showing the brace or stay in horizontal section. Fig. 4 is a vertical transverse section on the line 4 4 of Fig. 1, showing the parts on a larger scale. Fig. 5 is a vertical 70 transverse section on the line 5 5 of Fig. 1, showing the parts on a larger scale. Fig. 6 is a top plan view of the swing-bar. Fig. 7 is a detail perspective view of the yoke. Fig. 8 is a detail view of a saddle-bracket. Fig. 9 is a 75 vertical transverse section on the line 9 9 of Fig. 1. Fig. 10 is a sectional view of the lower end of a post and the stirrup-support therefor, showing the manner of connecting them, the parts being illustrated on a larger 80 scale. Fig. 11 is an end view of a post. Fig. 12 is a detail perspective view of the rocker-crank, brake-shoe, and connections between said parts and the sole-plate and main frame. Fig. 13 is a vertical transverse section on the 85 line 13 13 of Fig. 1. Fig. 14 is a top view of the stay or brace, showing the means for connecting the same to the limb. Fig. 15 is a detail perspective view of the transverse bracket to which the swing-bar is connected. 90 Fig. 16 is a detail perspective view of the bracket secured to the crown of the front fork and having a pin-and-slot connection with the sole-plate.

Corresponding and like parts are referred 95 to in the following description and indicated in all the views of the drawings by the same reference characters.

The appliance comprises a sole-plate 1, preferably of a shape to conform to the outline of the sole of a shoe, said plate likewise being formed, preferably, of metal flange at its edges to stiffen and strengthen the same and provide convenient means for attachment of the coöperating parts therewith. 105 Suitable means are provided for attachment of the device to the foot of the user, and, as shown, they consist of clamps arranged near the front and the rear of the said sole-plate, each of the clamps comprising complementary 110 jaw-pieces 2 and a connecting right-and-left-hand threaded screw 3, which is adapted to

be turned by means of a key in the manner well understood. A post 4, fixed to the sole-plate 1, prevents movement of the screw 3 transversely of the sole-plate and prevents 5 relative lateral displacement of the clamp and the device when secured to the foot. A heel-clip 5 projects upward from the sole-plate 1 and prevents forward displacement of the appliances.

10 A frame 6 is located below the sole-plate and is preferably of tubular formation, being formed of a sheet-metal blank rolled upon itself and having its edge portions overlapped and riveted or otherwise secured. The tubular or hollow frame 6 is perforated to 15 secure lightness of structure and to add to its appearance. A fork is provided at the rear end of the frame 6 and is preferably an integral part thereof, the fork sides 7 straddling 20 the rear wheel 8, which is mounted upon an axle 9, secured to the extremities of the fork members in any desired way. The front wheel 10 is mounted upon an axle 9, supported in the extremities of the side members of 25 the front or steering fork 11, the crown or head of the latter being preferably hollow or tubular and having a relative upward and rearward inclination and pivotally connected to the forward end of the frame 6, so as to 30 turn about an axis inclined to the perpendicular. The steering-fork 11 is preferably formed of a sheet-metal blank rolled upon itself and having the edge portions overlapped and riveted or otherwise secured.

35 The front end of the frame 6 is inclined and is closed by means of a plate 12, which acts as a reinforcement. Integral lugs 13 project from the head or crown of the fork 11 and coöperate with corresponding lugs 14, projected forward from the frame 6, the two sets of lugs 13 and 14 overlapping and having 40 corresponding openings to receive tapered pivot-fastenings 15, by means of which the steering-fork is pivotally connected to the frame 6. The lugs 14, while shown as being 45 separate from and attached to the frame 6, may be a part thereof. Other lugs 16 and 17 project from the head of the steering-fork and may be separate therefrom or form a 50 part thereof and are apertured to receive the pivot-fastenings 15. The lugs 14 are received in the spaces formed between the respective lugs 17 and 16 and the lugs 13. The lug 17 is a rear extension of a bracket 18, 55 which is secured to the head of the steering-fork 11, the horizontal portion of said bracket having a longitudinal slot 19, which is reinforced by means of a flange and which is adapted to receive the lower end of a pin 20, 60 firmly attached to the sole-plate 1 and pendent therefrom and braced by means of a stay-piece 21. The pin 20 and bracket 18 in the relation disclosed admit of a limited longitudinal movement of the sole-plate and frame 65 6, while at the same time preventing lateral

displacement of said parts and at the same time holding them in transverse alinement.

Posts 22, located upon opposite sides of the wheel 10 and sole-plate, have a ball-and-socket connection at opposite ends with, respectively, said sole-plate and hangers connected to the side members of the steering-fork. The posts 22 are preferably tubular and their ends are made rounding and formed with an angular opening 23, in which is fitted 75 a corresponding portion of a bolt or fastening 24 to prevent relative turning of the latter. V-shaped indentures are drawn inward, so as to form the rounded ends which constitute the ball members of the universal joints. A saddle-bracket 25 is secured to the front portion of the sole-plate, one upon each side thereof, and is formed with a socket 26 to receive the upper rounded end of the post 22, said socket having an opening at a central 80 point to receive the bolt or fastening 24, to the threaded end of which is fitted a nut 27 for securing the parts, said nut having a concavo-convex flange of a size to close the opening in the socket at all times. A stirrup 28 85 in the form of a hanger has its members attached to the side members of the steering-fork in any convenient and substantial way, and each stirrup is provided at its lower end with a socket 29, similar to the socket 26, to 90 receive the lower end of a post 22, the parts being connected in substantially the same manner as the upper ends of said posts to the sockets 26 to admit of a universal joint being provided between the lower ends of the posts 95 and the stirrups or hangers 28. A yoke 30 connects the lower ends of the stirrups or hangers 28 to prevent relative lateral displacement thereof either inward or outward, 100 said yoke being of U form and having the extremities of its members connected to lugs of the stirrups 28.

The sole-plate 1 has a limited longitudinal movement and a lateral rocking movement, the former being designed for actuation of the 105 brake mechanism and the latter adapted to control the steering by admitting of pressure being applied to one or the other of the posts 22, whereby the steering-fork is caused to turn and direct the movement of the device 110 to one side or the other from a straight course. To hold the sole-plate and frame in a given position and to lend a degree of stability to the device, springs 31 are located upon opposite sides thereof and have connection at one 115 end with the sole-plate and at the opposite end with the frame, said springs being of the contractile type and arranged to have a relative upward and forward inclination and adjustable to provide for varying their effective 120 tension or force. The upper forward ends of the springs 31 have adjustable connection with the sole-plate by means of a series of openings 32, formed in the longitudinal flanges thereof and into any one of which the 125

said springs are adapted to engage. By moving the upper ends of the springs 31 forward or backward their relative inclination as well as the effective tension may be varied 5 to suit existing conditions. The lower rear ends of the springs 31 are adjustably connected with the frame by means of eyebolts 33, brackets 34, and set-nuts 35. The brackets 34 are riveted or otherwise fastened to opposite sides of the frame 6, and their off-standing portions are apertured to receive eyebolts 33, upon which are threaded the set-nuts 35. By turning the set-nuts 35 either to the right or to the left the eyebolts are 10 moved longitudinally, with the result that the tension of the springs 31 is varied or adjusted to suit the weight and strength of the user as may be required. Considering the sole-plate to be relatively fixed as when secured to the 15 foot, the springs 31 by reason of their upward and forward inclination tend to throw the frame 6 upward and forward with the pin 20 at the rear end of the sole 19 of the bracket 18. The forward movement of the frame 6 is also 20 limited by means of a pin or stud 36, let into the rear portion of the sole-plate and arranged to operate in a longitudinal slot 37, formed in the upper horizontal portion of a bracket 38, riveted or otherwise fastened to the frame 6. 25 Under normal conditions the pin or stud 36 occupies a position at the rear end of the slot 37. The pin or stud 36 also materially assists in holding the sole-plate and frame in alignment and from transverse displacement, 30 thereby supplementing the action of the pin 20 and bracket 18.

A rocker-crank 39 connects the rear portion of the sole-plate with the rear portion of the frame 6 and normally inclines upwardly 40 and forwardly, so that pressure applied thereto in a perpendicular direction will cause it to rock and effect a relative longitudinal movement of the sole-plate and frame, whereby said parts receive a simultaneous movement 45 toward each other, with the result that the brake mechanism is automatically set. The rocker-crank 39 has its crank-arms 40 journaled to the side members of the rear fork 7 and its middle portion journaled to the sole-plate, 50 said middle portion having a crimp or bend 41, which is mounted in the bearing provided upon the sole-plate and which bearing consists of a bed-piece 42 and cap-piece 43, both pieces being riveted or otherwise fastened to each other and to the sole-plate. The 55 cap-piece 43 is formed with pendent ears 44, between which the upper end of a link 45 is pivoted, said link supporting the brake-shoe 46, provided for cooperation with the rear 60 wheel 8. A frame 47 of approximately H form is pivotally connected at one end to the frame 6 and similarly connected at the opposite end to the link 45 and brake-shoe 46, the frame 47 and link 45 forming, in effect, a toggle connection between the sole-plate and frame 6 to compel an application or a release of the brake, according as the parts 1 and 6 are relatively moved in one or the other direction. The brake-shoe is prevented from lateral displacement by having one end come 70 between the side members of the fork 7 and its opposite end come between the side portions of the crank-hanger 39. Cap-plates 48 confine the crank-arms 40 of the crank-hanger in the seat or bearings formed in the side 75 members of the rear fork 7. When the weight is about evenly distributed upon the sole-plate, the frame 6 occupies a normal position about as shown in Fig. 2, the tension of the springs 31 being such as to hold the frame 80 6 forward; but in the event of an abnormal weight coming upon the rear portion of the sole-plate either voluntarily or involuntarily on the part of the user the rocker-crank 39 will turn in its bearings upon its crank portions and cause the frame 6 to move rearward or the sole-plate to relatively move forward, with the result that said parts 1 and 6 will relatively approach simultaneously with the longitudinal movement, and thereby 85 cause the brake-shoe 46 to bear with a greater or less force upon the frame of the rear wheel 8, and thereby check the speed and admit of the parts assuming a stable or normal condition. Should the user from any cause lose his 90 or her equilibrium and the feet tend to move forward in advance of the center of gravity, the weight will be automatically shifted onto the rear portion of the sole-plates, and thereby involuntarily set the brake and afford 95 opportunity for the party to recover his or her equilibrium, and thereby avoid a fall. The same result takes place when going downgrade and there is a tendency for the feet to move forward of the center of gravity. 100 As a utility-brake the speed may be perfectly controlled by shifting of the weight upon the rear portion of the sole-plate, which may be accomplished by a deft movement of the foot, 105 as will be readily comprehended.

A stay or brace is provided to strengthen the ankles and prevent turning of the device under the foot. This stay or brace is located upon one side of the appliance and comprises telescopic sections 49 and 50, the latter being 110 tubular and the former arranged to operate therein. Means are provided for connecting the upper end of the stay or brace to the leg, preferably at a short distance below the knee, and said means comprise a strap 51 and a 115 curved plate 52, the strap 51 being constructed to be buckled about the leg and the plate 52 serving to prevent injurious pressure of the upper end of the stay against the limb. A bolt or fastening 53 pivotally connects the 120 plate 52 with the upper end of the stay, the head of said fastening being countersunk in the plate, so as not to exert pressure upon any one part of the limb. The outer end of the fastening 53 catches loosely in an opening 125 130

in the upper end of the stay and is retained in place by means of a pair of nuts 54. The lower portion of the stay or brace is flattened and has adjustable connection with a transversely-arranged swinging bar 55. The swinging bar has an upright portion 56 at one end, composed of spaced members, between which the lower portion of the section 50 is received and to the upper ends of which members a stay or brace is pivotally connected by the fastening 57. A slot 58 is formed in the lower portion of the stay or brace, and a bolt or like fastening 59 passes therethrough and through corresponding openings in the lower ends of the members of the upright portion 56, and which serves to secure the brace or stay when moved to the required adjusted position. The swing-bar 55 has a link connection with a bracket 60, secured to the frame 6, and is preferably formed of a sheet-metal blank folded upon itself. The link 61 has pivotal connection at its lower end with the bar 55 and like connection at its upper end with the bracket 60. The link 62 is rigid with the bar 55, being preferably an integral part thereof and formed by bent end portions of the blank arranged to overlap each other, and having pivotal connection at its upper end with the bracket 60. The pivot-fastenings 63 between the links and the bracket 60 are in transverse alignment and are arranged in such a manner as to admit of the parts 1 and 6 having a relative longitudinal and lateral rocking movement, whereby the brake mechanism and the steering mechanism are under perfect control. The bracket 60 is formed at opposite ends with uprights 64, which embrace opposite sides of the frame 6 and are riveted or otherwise attached thereto, the middle portion of the horizontal part being firmly attached to the under side of the frame 6. The telescopic arrangement of the stay or brace provides for adjusting the appliances to the leg and at the same time admits of a limited play, made necessary to provide for lateral angular movement of the sole-plate when it is required to steer either to the right or to the left of a direct course.

The ground or supporting wheels may be of any formation, but in the preferable construction each is formed of disks or side plates 65, secured near their edges and having their middle portions oppositely deflected and formed with inner flanges 66, and their flanges 67 forming seats to receive ball-cups 68. A tube 69 is fitted to the inner flanges 66 and may be threaded or otherwise secured thereto and firmly unites the disks or plates at a central point. The outer edges of the disks or plates are flared, as shown at 70, and have inner flanges 71, forming the tread to which a tire or rim 72 is fitted, said tire consisting of a channel-iron, the side flanges of which embrace opposite sides of the flared

portions 70. Balls 73 are confined between the cups 68 and cones 74 provided upon the axle 9. A wheel constructed in this manner is light, strong, and durable and is best adapted for the purpose. The disks or side plates 65 may be perforated, if desired, to increase the lightness and add to the appearance of the device.

Having thus described the invention, what is claimed as new is—

1. In a pedemobile or appliance of kindred nature, the combination of a main frame, a sole-plate, connecting means between the two to admit of a lateral rocking of the sole-plate, a steering-fork providing a support, and connecting means between the steering-fork and sole-plate, whereby a shifting of the weight laterally to one side or the other of a medial line causes a corresponding movement of the steering-fork, thereby admitting of controlling the direction of travel.

2. In a pedemobile or analogous device, the combination of a main frame, a sole-plate connected thereto and adapted to receive a lateral rocking movement, a steering-fork provided with a support, and independent connections between opposite sides of the sole-plate and the side members of the steering-fork for transmitting excessive lateral pressure to said fork to effect a turning thereof when it is required to depart from a direct course.

3. In a pedemobile or like appliance, the combination of a main frame and a sole-plate connected to admit of lateral angular movement of the sole-plate, a steering-fork provided with a support, and independent connections between opposite sides of the sole-plate and the side members of the steering-fork and having a universal connection with each to admit of relative lateral angular movement and longitudinal movement of the sole-plate and main frame.

4. In a pedemobile or like appliance, the combination of a main frame, a sole-plate, connections between the two to admit of their relative longitudinal and lateral angular movements, a steering-fork pivotally connected with the main frame and provided with a support, and upright connections at opposite sides of the device and having a ball-and-socket connection at its ends with the sole-plate and the side members of the steering-fork to admit of the various relative arrangements of the parts and to positively transmit excessive lateral pressure upon the sole-plate and the steering-fork to effect proper direction of travel.

5. In a pedemobile or like appliance, the combination of a sole-plate and a main frame connected to admit of relative lateral angular movement of the sole-plate, a steering-fork having pivotal connection with the main frame, uprights at opposite sides of the device, saddle-pieces at opposite sides of the

sole-plate receiving the upper ends of said uprights, and stirrup-pieces connected to the side members of the steering-fork and receiving the lower ends of said uprights.

5. In a pedemobile or like device, the combination of a main frame, a sole-plate connected therewith and adapted to receive a relative lateral angular movement, a steering-fork having pivotal connection with the main frame, uprights at opposite sides of the device provided with rounded ends, saddle and stirrup pieces applied to, respectively, the sole-plate and side members of the steering-fork having sockets to receive the rounded ends of said uprights, and positive connecting means between the rounded ends of the uprights and the sockets of said saddle and stirrup pieces.

6. In a pedemobile or like appliance, the combination of a sole-plate, a main frame connected thereto to admit of the sole-plate having relative lateral angular movement, a steering-fork, opposite connections between the sole-plate and the members of the steering-fork, and means connecting the lower ends of said opposite connections to prevent relative lateral play thereof.

7. In a pedemobile or like appliance, the combination of a sole-plate, a main frame connected thereto to admit of the sole-plate having relative lateral angular movement, a steering-fork, opposite connections between the sole-plate and the members of the steering-fork, a yoke of approximately U form joining the lower ends of said opposite connections.

8. In a pedemobile or like appliance, the combination of a main frame, a sole-plate connected thereto to admit of its receiving a relative lateral angular movement, a steering-fork pivotally connected to the main frame and provided with a support, stirrups or hangers attached to the side members of the steering-fork, uprights loosely joined at their lower ends to the stirrups or hangers, and a yoke of approximately U form having its members connected to the lower ends of said uprights and to the lower ends of the stirrups or hangers.

9. In a pedemobile or like appliance, the combination of a main frame, a sole-plate connected thereto and adapted to have a relative lateral angular movement imparted thereto, a steering-fork pivotally connected to said main frame, connecting means between the sole-plate and steering-fork for transmitting excessive lateral pressure to the latter, and connecting means between the sole-plate and head or crown of the steering-fork to hold the parts in transverse alignment.

10. In a pedemobile or like appliance, the combination of a main frame, a sole-plate connected thereto and adapted to have a relative lateral angular movement imparted

thereto, a steering-fork pivotally connected to said main frame, connecting means between the sole-plate and steering-fork for transmitting excessive pressure to the latter, and a pin-and-slot connection between the sole-plate and the head or crown of the steering-fork.

11. In an appliance of the character specified, the combination of a main frame, a relatively movable sole-plate connected thereto, a steering-fork having pivotal connection with the main frame, means for transmitting excessive lateral pressure from the sole-plate to the steering-fork to effect positive movement of the latter for controlling the direction of travel, and means for exerting a yielding force between the main frame and sole-plate to hold the parts in a given position under normal conditions.

12. In an appliance of the character specified, the combination of a main frame, a relatively movable sole-plate connected thereto, a steering-fork having pivotal connection with the main frame, means for transmitting excessive lateral pressure from the sole-plate to the steering-fork to effect positive movement of the latter for controlling the direction of travel, and means for exerting a yielding force between the main frame and sole-plate to hold the parts in a given position under normal conditions, and means for varying the effective force of said yielding-pressure-exerting means.

13. In an appliance of the character specified, the combination of a main frame, a relatively movable sole-plate connected thereto, a steering-fork having pivotal connection with the main frame, means for transmitting excessive lateral pressure from the sole-plate to the steering-fork to effect positive movement of the latter for controlling the direction of travel, means for exerting a yielding force between the main frame and sole-plate to hold the parts in a given position under normal conditions, and means for varying the effective force of said yielding-pressure-exerting means.

14. In an appliance of the character specified, the combination of a main frame, a relatively movable sole-plate connected thereto, a steering-fork having pivotal connection with the main frame, means for transmitting excessive lateral pressure from the sole-plate to the steering-fork to effect positive movement of the latter for controlling the direction of travel, side springs connecting the main frame with the sole-plate, and means for varying the effective tension of said side springs.

15. In an appliance of the character specified, the combination of a main frame, a relatively movable sole-plate connected thereto, a steering-fork having pivotal connection with the main frame, means for transmitting excessive lateral pressure from the sole-plate to the steering-fork to effect positive movement of the latter for controlling the direction of travel, side springs having a relative upward and forward inclination and connecting the main frame with the sole-plate, and means for changing the relative inclination of said side springs.

16. In an appliance of the character specified, the combination of a main frame, a relatively movable sole-plate connected thereto, a steering-fork having pivotal connection with the main frame, means for transmitting excessive lateral pressure from the sole-plate to the steering-fork to effect positive move-

- ment of the latter for controlling the direction of travel, side springs having a relative upward and forward inclination and connecting the main frame with the sole-plate, 5 means for changing the relative inclination of said side springs, and other means for changing the effective tension of said side springs.
17. In a pedemobile or like appliance, the combination of a main frame, a sole-plate 10 connected thereto and having a relative longitudinal movement, and a brake mechanism thrown into and out of action by the relative longitudinal movement of the sole-plate and main frame.
18. In a pedemobile or like appliance, the combination of a main frame, a sole-plate connected to and having a relative longitudinal movement, a brake, and a rocker connection between the sole-plate and main frame 15 and normally inclined from the perpendicular, whereby a shifting of the weight upon the sole-plate effects a relative longitudinal movement of the sole-plate and main frame and automatically sets the brake.
19. In an appliance of the character specified, the combination of a main frame, a sole-plate connected thereto and having a relative longitudinal movement, a brake-shoe, and a toggle connection between said brake-shoe 20 and the sole-plate and main frame.
20. In an appliance of the character set forth, the combination of a main frame, a sole-plate connected thereto and adapted to have a relative longitudinal movement imparted thereto, a rocker connection between 25 the sole-plate and main frame, and a brake having a toggle connection with the sole-plate and main frame and automatically set by shifting of the weight upon the sole-plate.
21. In an appliance of the character set forth, the combination of a main frame, a sole-plate connected thereto and adapted to receive a longitudinal movement, a rocker connection between the sole-plate and main 30 frame and normally inclined to the perpendicular, a spring connection between the sole-plate and main frame for normally holding the parts in a given position, and a brake adapted to be automatically applied upon 35 relative longitudinal movement of the sole-plate and main frame due to voluntary or involuntary shifting of the weight from the front to the rear portion of the sole-plate.
22. In a pedemobile or like appliance, the 40 combination of a main frame, a sole-plate connected thereto and adapted to have imparted thereto a relative longitudinal and lateral angular movements, a steering-fork pivotally connected with the main frame, opposite rigid connections between the sole-plate 45 and side members of the steering-fork and having a universal connection with each, spring-connecting means between the main frame and sole-plate for normally holding the parts in a given position, a pin-and-slot connection between the steering-fork and sole-plate, a similar pin-and-slot connection 50 between the sole-plate and main frame, a rocker connection between the sole-plate and main frame and normally inclined to the perpendicular to effect a relative longitudinal movement of the sole-plate and the main frame upon abnormal shifting of the weight, and a brake automatically applied when said sole-plate and main frame receive a relative longitudinal movement. 55
23. In combination with a pedemobile or like appliance, a side stay or brace composed of telescoping sections and having adjustable connection at its lower end with said appliance, and means applied to the upper end thereof for connection of the brace to the limb of the user. 60
24. In combination with a pedemobile or like appliance, a stay or brace provided with means for attachment to the limb of the user, 65 means connecting the lower end of said stay with the appliance to admit of the latter having a limited angular play in a vertical plane.
25. In combination with a pedemobile or like appliance, a swing-bar connected thereto and having a side extension, and a stay or brace having adjustable connection with the extension of said swing-bar. 70
26. In combination with the main frame of a pedemobile or like appliance, a bracket connected thereto, a swing-bar having link connection with opposite ends of the bracket and provided with an extension at one end, and a stay or brace having adjustable connection with said extension. 75
